Design No. 572

*N. S. Vedder's
design of cook stove*

Patented June 28, 1853.

Wes. 572

N. S. Vedder, of Troy, N. Y.

Letters Patent No. 572 Dated June 28th 1853.

uuuuu

The schedule referred to in these Letters Patent and making part of the same

uuuuuuu

To all whom it may concern:

Be it known that I, N. S. Vedder, of Troy, in the County of Rensselaer, and State of New York, have invented or produced, a new and original design of elevated oven cook stove, which I call the "Florida Air Tight," and I do hereby declare that the following, is a full, clear and exact description of the same, reference being had to the annexed perspective drawing making a part of this specification.

The ornamental design of my cook stove, consists in the arrangement of the rose branch and roses (a, a,) on the front doors B, B, and on the jamb doors and panels C C C, the elevated oven D, is ornamented on the front plate E, with the rose branch (b, b) and on the centre panel with the ornament (C), the oven door F, is ornamented with the ornament (d) on the panels, (c e e) are mouldings forming the cases or frames of the oven, front and jamb doors, G, is the top oven plate, surrounded with the moulding (f), H, and I, are the top and bottom plates, surrounded with the mouldings (g g), J, is the front plate, and K, is the jamb, I, is the leg ornamented with the leaves (i) —

Wes.

582

Having thus described my design of Cook Stove, What I claim as new, and desire to secure by letters patent, is the ornamental design and configuration of Cook Stove plates, such as herein described, and represented in the annexed drawing.
